BY *Victor J. Evans*

INVENTOR

ATTORNEY

UNITED STATES PATENT OFFICE.

JOSEPH A. CALDWELL, OF ARKADELPHIA, ARKANSAS.

BEDSTEAD.

Application filed April 15, 1922. Serial No. 553,155.

To all whom it may concern:

Be it known that I, JOSEPH A. CALDWELL, a citizen of the United States, residing at Arkadelphia, in the county of Clark and 5 State of Arkansas, have invented new and useful Improvements in Bedsteads, of which the following is a specification.

The object of this invention is to provide the head board and the foot board each with 10 an adjustably mounted element which shall serve to ward off drafts in cold weather, but which may be shifted, when desired to permit of free circulation of air.

A further object is to provide a vertically 15 slidable element, for the head board or foot board, or both of these elements, the slidable element serving the purpose indicated.

With the foregoing and other objects in view, the invention consists in the novel construction and arrangement of elements described and claimed, it being understood 20 that modifications may be made within the scope of the claims without departing from the spirit of the invention.

25 In the drawings, Figure 1 is a perspective view of a bedstead having my improvement applied thereto; Figure 2 is a fragmentary view showing one end of the footboard as being slidable in a vertical groove in the adjacent post; Figure 3 is a detail on line 3—3 of Figure 2.

The headboard of a bedstead is designated 10, the foot board is shown at 11, and the side rails are designated 12 and 13. The 30 head board and foot board are each provided with a vertically slidable element, such as

14 and 15. These elements are of an ornamental character and may each include a series of panels, or these devices may be otherwise formed, provided the main purpose thereof is capable of realization.

The vertical posts 16 of the head board and foot board are provided with grooves extending lengthwise thereof, and the elements 14 and 15 operate in these grooves, or 45 channels. The channels terminate a short distance above the bottom portions of the vertical posts, and provide stops 20 for limiting the downward movement of the device. Securing devices 23 and 24 are provided in 50 connection with each element 14 and 15, and are mounted near the corner portions thereof, and are adapted to engage recessed portions of the posts, for retaining the slidable elements in the position desired.

55 By the use of these devices, the necessity of providing an excessive amount of covering in extremely cold weather is avoided.

Having thus described the invention, I claim:

A bedstead including a head board and a foot board, the elements of which are provided with vertical grooves, and air deflecting devices movable bodily in vertical planes in said grooves, said deflecting devices being 65 slidable to a point permitting their upper edges to assume a position approximately flush with the upper surface of a mattress when placed on the bedstead.

In testimony whereof I affix my signature.

JOSEPH A. CALDWELL.
